UNITED STATES PATENT OFFICE.

DAVID H. TALNOPER, OF NEW YORK, N. Y.

ADJUSTABLE DIE-HOLDER FOR PUNCH-PRESSES AND THE LIKE.

1,256,615.

Specification of Letters Patent. Patented Feb. 19, 1918.

Application filed August 4, 1913. Serial No. 782,834.

To all whom it may concern:

Be it known that I, DAVID H. TALNOPER, a citizen of the United States, residing in the borough of Manhattan, city, county, and State of New York, have invented a certain new and useful Improvement in Adjustable Die-Holders for Punch-Presses and the like, of which the following is a specification.

The invention relates to an improvement in machines for punching holes or for making buttons and has for its objects to produce a device by means of which the tool may be positively set in any desired position; to protect the operator from injury while operating the machine and to improve the efficiency of such machines.

These and further objects will more fully appear from an examination of the specification and accompanying drawings taken together or separately.

My invention is illustrated in the drawings in which the same parts are designated by similar reference characters in all the figures and in which—

25 Figure 1 is a side elevation of a press equipped with my improvement.

Fig. 2 is a front elevation partly in section of the device.

Fig. 3 is a section on the line 3—3 of 30 Fig. 2 showing a shell carrier in position, and

Fig. 4 is a section on the line 4—4 of Fig. 2.

I will describe my present invention as 35 employed in a machine for covering buttons, but it is obvious that the device may be used in other analogous devices, such for instance, in substituting a punch and die for the button blank carrying devices illustrated.

40 In the embodiment illustrated the apparatus comprises a base or table 1, which may be supported on legs (not shown). The base is provided with a standard 2, which carries horizontal arms 3—3; carried on the 45 arms is a head 4, in which is mounted a sliding block 5; which is provided with a stop 6, for limiting its downward movement.

Pivoted in the standard 2 is a lever 7 which has a treadle (not shown) at its 50 lower end; said treadle being used to operate the machine in the usual manner. The upper end of the lever is provided with a head 8, which works in a socket 8' in the block 5.

55 An anvil 9 is permanently secured to the

base 1, and is provided with a sleeve 10 which is normally held up by a spring 11.

Carried by the block 5 is a mandrel 12, having a concave lower face 13. The mandrel is provided with a carrying sleeve 14, 60 upon which is a rib or collar 15. A catch or link 16 is pivoted at 17 to the mandrel 12 and is provided with a notch 19 which engages the rib or collar 15 and retains the carrying sleeve in position on the mandrel. 65 The link is provided with a cam face 20 for a purpose to be hereinafter described.

The upper end of the mandrel 12 is provided with a screw threaded extension 21 fitting a socket 23, in a bushing or extension 22, carried in a socket in the sliding block 5. The block 5 is provided with a set screw 26 which engages a groove 25 in the bushing in such a manner as to prevent it from falling from the socket and at the same time 75 allowing it to turn therein.

A pin 27 is carried in the block 5 in such a manner that it is partly cut away to form part of the wall of the socket, and it is provided with a thumb nut 28 by means of 80 which the pin may be drawn forward thereby securely clamping the bushing in place in the socket. Any other device, such as a set screw, may be used for this purpose. The bushing or extension is provided with 85 a shoulder 24, which rests against the lower face of the sliding block and limits the distance the bushing may be inserted in the block and takes up the thrust.

A carrier for the lower part of the button 90 is provided. This carrier, as shown in Figs. 2 and 3, comprises a thimble or nipple 29 which is provided at its top with a socket 33 for the reception of the shell, tuft piece 34 and filling piece 35. The thimble 29 is 95 slidably mounted in a sleeve 30 and is normally held by friction in the upper part of the sleeve. A pin carried by the sleeve engages in a slot in the thimble and prevents the latter from being withdrawn from 100 the sleeve. The upper part of the sleeve 30 is curved and of such diameter as to be engaged by the end of the catch 16 when the latter is lowered. The carrier is adapted to be supported on the upper part of the 105 sleeve 10 during a certain step in the manufacture of a button and is shown in position in Fig. 3.

In operation the catch or link 16 should always be on that side of the mandrel oppo- 110

site the operator so as to be out of the way of the operator's fingers when he is inserting the pieces to be operated on in position. This is made possible by my invention. The 5 mandrel is screwed into the bushing, the thumb nut 28 is loosened, the bushing and mandrel are now turned until the catch or link is in its proper position and the thumb nut is screwed up. The parts are now 10 surely held in position and the machine is ready for operation.

My invention is particularly useful in machines making buttons or the like of shapes other than circular, as the mandrel may be 15 adjusted with the greatest nicety and the movable tool can be always brought into perfect alignment with the lower one.

By my invention by changing the contour 20 of the parts which carry the elements which go to make up the button, buttons of square, oblong, elliptical, or oval shape may, on account of the perfect adjustment of the bushing, be made as readily as circular ones.

The operation of the device illustrated in 25 Figs. 2 and 3 is as follows: A shell is placed top uppermost on the anvil and a disk of covering material is laid over it. The mandrel and carrying sleeve are now brought down, the sleeve 10 is depressed against the 30 spring 11 and the shell and covering are forced into the carrying sleeve and held there by friction. The mandrel is now raised and the catch, by reason of its engagement with the rib in the carrying sleeve, carries the sleeve, and the covered shell with it.

While the above described operation has been going on, the attendant has placed the 40 collet carrying the tuft-piece and filling in the nipple 29 which is in place in the sleeve or carrier 30. When the bushing and mandrel have reached the highest point of their

travel the carrier is placed in position upon the anvil and rests in the socket of the sleeve 10, as shown in Fig. 3. The sliding block 45 is again depressed. The cam on the catch will engage the curved face of the carrier 30 and be moved from engagement with the rib 15. The carrying sleeve 14 will rest upon the carrier and the mandrel will move 50 relatively to it and force the shell and cover onto the thimble 29 and over the collet whereby the parts of the button are firmly secured together.

Having now described my invention what 55 I claim as new and desire to secure by Letters Patent is:

1. In a press, the combination with a frame and an anvil, a block movable in the frame, a bushing rotatable in the block, 60 means for locking the bushing against rotation, a mandrel carried by the bushing, said mandrel coöperating with the anvil, a sleeve carried on the mandrel, a catch carried by the mandrel and supporting the sleeve, of 65 means whereby the mandrel may be adjusted to bring the catch in proper position relative to the frame of the press.

2. In a press, the combination with an 70 anvil and a mandrel coöperating therewith, a sleeve carried by the mandrel, a catch carried by the mandrel and supporting the sleeve, of an extension or bushing operatively supporting the mandrel, means for 75 rotatably securing the extension or bushing to a movable part of the press, and means for securing the extension or bushing against rotation.

This specification signed and witnessed this 29th day of July, 1913.

DAVID H. TALNOPER.
